[57] CLAIM

The ornamental design for a wind spinner, as shown and described.

DESCRIPTION

FIG. 1 is a front elevational view of a wind spinner showing my new design, the rear being a mirror image;

FIG. 2 is a left side elevational view thereof, the right side being a mirror image;

FIG. 3 is a bottom plan view thereof;

FIG. 4 is a top plan view thereof;

FIG. 5 is a front elevational view of a second embodiment of FIG. 1, the difference residing in the change in shape, the rear being a mirror image and the other sides being essentially the same as FIGS. 2-4;

FIG. 6 is a front elevational view of a third embodiment of FIG. 1, the difference residing in the change in shape, the rear being a mirror image and the other sides being essentially the same as FIGS. 2-4; and,

FIG. 7 is a front elevational view of a fourth embodiment of FIG. 1, the difference residing in the change in shape, the rear being a mirror image and the other sides being essentially the same as FIGS. 2-4.
